UNITED STATES PATENT OFFICE.

HENRY L. GOODWIN AND JOHN G. LUND, OF MINNEAPOLIS, MINNESOTA.

SAFETY DOOR-LOCK FOR ELEVATORS.

1,146,153.

Specification of Letters Patent. Patented July 13, 1915.

Application filed July 14, 1913. Serial No. 778,879.

To all whom it may concern:

Be it known that we, HENRY L. GOODWIN and JOHN G. LUND, citizens of the United States, residing at Minneapolis, in the county of Hennepin and State of Minnesota, have invented certain new and useful Improvements in Safety Door-Locks for Elevators; and we do hereby declare the following to be a full, clear, and exact description of the invention, such as will enable others skilled in the art to which it appertains to make and use the same.

Our invention has for its object to provide a highly efficient and simple safety device for elevator doors, and to this end it consists of the novel devices and combinations of devices hereinafter described and defined in the claims.

In the accompanying drawings, which illustrate the invention, like characters indicate like parts, throughout the several views.

Referring to the drawings, Figure 1 is a perspective view showing our invention applied, in working position, to an elevator, some parts being broken away. Fig. 2 is a front elevation of the parts shown in Fig. 1, but on a somewhat smaller scale, and with the elevator car in different position. Fig. 3 is a view, principally in vertical section, taken on the line $x^3 x^3$ of Fig. 1, on an enlarged scale; and Fig. 4 is a detail view, principally in section, taken on the line $x^4 x^4$ of Fig. 3, on an enlarged scale.

The numeral 1 indicates one of the floors of a building; through which is extended an elevator shaft 2. A door opening 3 is formed in the casing 4 of the elevator shaft between posts 5 and 6. An elevator car 7 is raised and lowered in the elevator shaft 2 by cables 8, and is held for straight line movement by upright guides 9. In one side of the elevator car 7 is formed a door opening 10, arranged to be brought into registration with the door opening 3 in the elevator shaft. A sliding door 11 is provided for closing the door opening 3, and is mounted in the customary manner. The parts thus far described may be of the standard or any suitable construction.

Referring now in detail to our invention, the numeral 12 indicates a lock casing having a pair of reversely projecting ears 13, secured by rivets to the rear vertical member of the marginal frame of the door 11.

A lock lever 14 is mounted within the casing 12, and is intermediately pivoted thereto by a horizontally extended pin 15, anchored at its ends to the sides of said casing. The long or upper end of the lock lever 14 is provided with a lock head 16, and the short or lower end thereof is provided with a roller equipped lateral extension 17. The lock head 16 and the roller equipped end of the lever extension 17 work through apertures 18 and 19, respectively, formed in the opposite edges of the lock casing 12. The lever extension 17 is seated in a transverse channel 19, formed in the lock lever 14, and is secured therein, for endwise adjustment, by a nut equipped bolt 20, seated in a perforation formed in the lock lever 14, and a longitudinally extended slot 21, formed in the inner end portion of the lever extension 17. By adjustably securing the lever extension 17 to the lock lever 14, the roller of said extension may be set in different positions, to move the lock head 16 different distances, as desired. It, also, permits the lock lever to be adjusted to different elevators wherein the widths between the door posts and the elevator vary. A leaf spring 22 is secured to the lock casing 12, and yieldingly holds the upper end portion of the lock lever 14 pressed against the lock casing 12, which acts as a stop, with its lock head 16 projecting through the aperture 19, as best shown by dotted lines in Fig. 3.

Formed in the inner vertical face of the door post 6 is a detent 23, with which the lock head 16 has interlocking engagement when the door 11 is in a closed position. A pair of vertically spaced and reversely beveled cam blocks 24 are secured to the elevator car 7, adjacent to its door opening 10, and are so arranged as to automatically retract the lock head 16 from the detent 23 when the elevator car 7 has reached a predetermined position, and thereby permit the door 11 to be opened. These cam blocks 24 are so arranged as to only permit the door 11 to open when the door openings 3 and 10 are in registration one to the other, and the floor of the elevator car 7 is in the same plane with the floor of the building.

Journalized in the inner ends of the cam blocks 24 is a vertically extended cam roller 25, over which the roller of the lever extension 17 travels axially, as the said roller passes from one cam block 24 to the other,

and which also serves to hold the lock head 16 in a retracted position. When the elevator car 7 is stopped at one of the floors, the roller of the lever extension 17 rests on the 5 cam roller 25 and the door 11 is unlocked and free to be moved into an open position. When the elevator car 7 does not stop at one of the floors, the roller of the lever extension 17 passes over the cam blocks 24 and the cam 10 roller 25, thereby withdrawing the lock head 16 from detent 23 and unlocking the door 11 for an instant. As soon as said roller has passed over the cams, the spring 22 is permitted to again force the lock head 16 into 15 engagement with the detent 23. During the opening movement of the door 11, the roller of the lever extension 17 is moved radially out of engagement with the cam roller 25, but not until after the lock head 16 is moved 20 laterally pass the detent 23. At the extreme closing movement of the door 11, the roller of the lever extension engages the roller 25, and is cammed thereby into a position to retract the lock head 16, thus permitting the 25 same to pass the door post 6 into a position where the same would again enter the detent 23, when the elevator is moved a sufficient distance to carry the roller of the lever extension 17 out of engagement with the cam 30 acting abutment.

For automatically closing the door 11, in either direction of travel of the elevator car 7, a zigzag cam bar 26 is secured to the front of the elevator car 7, and a roller 27, for co-operation therewith, is journaled in a bearing 28 secured to the frame of the door 11 just beneath the lock casing 12. The intermediate portion of the cam bar 26 is located a sufficient distance from the roller 27 to 35 permit the door 11 to be opened the full width of the doors openings 3 and 10. The end portions of the cam bar 26 are so arranged as to engage the roller 27, in either direction of travel of the elevator car 7, and thereby 40 cam the door 11 into a closed position where the same will be automatically locked by the head 16 and co-operating detent 23. The extreme end portions of the cam bar 26 are curved laterally to permit the roller 27 to 45 pass the same, during the travel of the car 7, without striking the same.

As is well known, a great many accidents have occurred by persons falling into elevator shafts when the doors have been accidentally left open, and by tripping and falling, in case the elevator is carelessly stopped with its floor either above or below the floor of the building. By the use of our improved device, elevator doors are positively held 55 locked, and cannot be opened, except when the elevator car is in a pre-determined position. Our invention, also, provides means for positively closing the elevator door, in case the same is accidentally left open by the 60 operator.

What we claim is:—

1. The combination with an elevator shaft, having a door opening, a sliding door, normally closing said door opening, and an elevator car arranged to be raised and lowered in said elevator shaft, of a yieldingly closed lock carried by said door, for securing the same in a closed position, and a fixed abutment, carried by said elevator car, for engagement with said lock, for automatically retracting the same, when said elevator car has reached a predetermined position in either direction of travel, said abutment also arranged to be engaged by said lock, during the closing movement of said door, for retracting said lock. 70

2. The combination with an elevator shaft, having a door opening a detent in the elevator shaft casing, a sliding door normally closing said door opening, and an elevator car arranged to be raised and lowered in said elevator shaft, of a spring held lock-lever, carried by said door and normally having interlocking engagement with said detent, and a fixed abutment, carried by said elevator car for retracting said lock lever, when said elevator car has reached a predetermined position in either direction of travel, said abutment also arranged to be engaged by said lock-lever, during the closing movement of said door, for retracting said lock lever. 85

3. The combination with an elevator shaft having a door opening, a sliding door normally closing said door opening, and an elevator car arranged to be raised and lowered in said elevator shaft, of a spring held lock lever carried by said door, and having interlocking engagement with a detent in the elevator shaft casing when said door is closed, and an abutment carried by said elevator car, and comprising a pair of reversely beveled cam blocks and a cam roller journaled between said cam blocks, said cam blocks arranged to retract said lock lever 100 when said elevator car has reached a predetermined position in either direction of travel, and said cam roller arranged to retract said lock lever by the final closing movement of said door. 110

4. The combination with an elevator shaft having a door opening, a sliding door normally closing said door opening, and an elevator car arranged to be raised and lowered in said elevator shaft, of a spring held lock lever intermediately pivoted to said door, said lever having at one end a lock head, and having at its other end an adjustable extension, said lock head having interlocking engagement with a detent in the elevator shaft casing when said door is closed, and an abutment carried by said elevator car, and comprising a pair of reversely beveled cam blocks, and a cam roller journaled between said cam blocks, said cam-blocks ar- 120

ranged to engage said lever extension, and to retract said cam head from said detent, when said car has reached a pre-determined position in either direction of travel, and
5 said cam roller arranged to be engaged by said lever extension during the closing movement of said door, thereby retracting said lock head.

In testimony whereof we affix our signatures in presence of two witnesses.

HENRY L. GOODWIN.
JOHN G. LUND.
